MACHINE FOR OPERATING ON INSOLES

Stanley M. Griswold, Newton, and Russell K. Nash, Brookline, Mass., assignors to United Shoe Machinery Corporation, Flemington, N. J., a corporation of New Jersey

Application July 30, 1940, Serial No. 348,522

17 Claims. (Cl. 12—20)

This invention relates to machines for applying reinforcing material to insoles such as are used in the making of welt shoes and particularly to machines for applying a strip of fabric such as duck or canvas to the inner face of the rib and to the insole adjacent to the rib. A machine of this type is disclosed in our Letters Patent of the United States No. 2,242,248, granted May 20, 1941.

Objects of this invention are to improve, simplify and render more convenient and efficient machines of this type. The machine disclosed in the above-mentioned patent comprises a strip guide, an applying roll movable into and out of operative position with respect to the insole and a spring-actuated finger which, as the applying roll approaches operative position, presses the strip against the applying roll. As illustrated herein, a finger operated in substantially the same manner as before is provided with a broad face to engage the portion of the strip which is applied to the body of the insole and press it against the applying roll, the said face being curved to correspond to the curvature of the applying roll and being provided with grooves in said face, the grooves being opposite to the pins or spurs on the applying roll so that if the spurs should extend through the strip they will extend into the grooves and not engage the face of the finger.

As in the machine of the prior patent, an outside guide is provided which engages the feather of the insole and the outer face of the rib and also an inside guide engaging the inner face of the rib. As illustrated herein, the inside guide is adjustably mounted on the finger above described which presses the strip against the applying roll. Thus, the inside guide is carried into operative position with respect to the inner face of the rib by the movement of the finger into operative position against the applying roll. The inside guide is adjustable heightwise with respect to the finger so that it may be set in accordance with the depth of the inside channel. As in the machine of the prior patent, upper and lower feed rolls are provided, the upper feed roll being movable toward the lower roll to engage the feather of the insole and cause it to be fed by rotation of the rolls. In the illustrated machine, the outside guide is formed on one end of a lever the fulcrum of which is at the rear of the machine and which lever between its ends is connected to the upper feed roll so that the outside guide is raised and low-

ered directly by movement of the upper feed roll into and out of operative position.

In the machine of the prior patent, shears are provided for cutting off the strip the blades of which are first moved bodily into position to embrace the strip and are then closed to cut off the strip. In the machine herein illustrated, shear blades operating in a similar manner are provided. The blades are arranged at an oblique angle to the length of the strip so that the severed ends of the strip, instead of being square, are substantially mitered, it having been found that ends so cut may be laid over each other at the end of the toe and secured to the insole without the necessity of applying additional cement where the strips overlap.

As in the machine of the prior patent, the illustrated machine is power driven and treadle-operated means is provided to set a clutch to start the machine, to move the upper feed roll into engagement with the insole, and to move the applying roll from inoperative to operative position, the treadle being held depressed during the operation of the machine. In the operation of the prior machine, it was found fatiguing to the operator to maintain the treadle depressed during operation of the machine throughout a day's run and accordingly the illustrated machine is provided with mechanism for relieving the operator substantially of the effort required to hold the treadle depressed.

The illustrated machine is provided with a more effective electrical unit for heating the strip and with improved means for moving the strip toward the heating element and the heating element toward the strip prior to the strip-applying operation and for insuring movement of the heating unit out of the way of the applying mechanism as the latter moves to inoperative position.

These and other features of the invention will appear more fully from the following detailed description when read in connection with the accompanying drawings and will be pointed out in the appended claims.

In the drawings,

Fig. 1 is a front elevation of the head of a machine embodying the present invention;

Fig. 2 is a side elevation of the head of the machine;

Fig. 3 is a side elevation of the lower part of the column of the machine showing the treadle mechanism;

Fig. 4 is a plan view of the mechanism for cutting off the strip;

Fig. 5 is a side elevation of parts shown in Fig. 4 and including the insole-feeding and strip-applying mechanism;

Fig. 6 is a detail, partly in section, of parts shown in Fig. 4;

Fig. 7 is a view, partly in section, showing the applying roll, the finger for pressing the strip against the applying roll and the inside guide carried by the finger;

Fig. 8 is a side elevation of parts shown in Fig. 6;

Fig. 9 is a sectional plan of the applying roll and the finger; and

Fig. 10 is a view of the face of the finger which engages the applying roll.

The illustrated machine is in its general organization substantially similar to that disclosed in the above-mentioned patent to which reference may be had for a more complete description thereof.

Briefly described, the machine comprises a column 10 on which is mounted a head plate 12 to which are secured two uprights 14, 16. In the uprights 14, 16 is journaled a shaft 18 carrying at its front end a lower feed roll 20 and at 25 its rear end a pulley 22 which is driven by a belt 23 from an electric motor through a clutch which is controlled by a treadle rod 24. The shaft 18 carries a gear 26 meshing with a gear 28 on a shaft 30 which has an upper feed roll 32 secured thereto, the beveled portion of the feed roll being provided with blunt teeth to enhance its feeding action. The shaft 30 at its rear end is loosely journaled in the upright 14 and near its front end is journaled in a block 34 guided for vertical movement to enable the feed roll 32 to be raised and lowered. Also journaled in the uprights 14, 16 above the shaft 30 is a rockshaft 36. Near the rear end of the shaft 36 are secured two laterally projecting arms 38, 40, the arm 38 (Fig. 1) being connected by a link 42 through yielding mechanism to an operating rod 44 (Fig. 3) downward movement of which will rock the shaft 36 in a counter-clockwise direction and move the arm 40 upwardly. To the arm 40 (Fig. 2) is pivoted at 46 a rod 48 the lower end of which passes through a lug 50 carried by a lever 52 fulcrumed at 54 to the frame and pivotally connected at 56 to the block 34. On the rod 48 is a spring 58 resting at its lower end upon the lug 50 and engaged at its upper end by a nut 60 threaded on the rod 48. Check nuts 62 threaded on the lower end of the rod 48 engage the lug 50 at the proper time in the movement of the arm 40 to raise the rear end of the lever 52, thus moving downwardly the block 34 in which the shaft 30 has its bearing and pressing the upper feed wheel 30 against the work.

At its front end the rockshaft 36 is bent to form an arm 64 upon which the applying roll and other operating instrumentalities of the machine are mounted. Secured by screws 66 to the arm 64 is a plate 68 carrying a stud 70 on which are freely mounted independently rotatable spurred disks 72, 73 and 74. On the inner end of the stud 70 is a head 76 which not only holds the spurred disks in place but serves to rub an upturned portion of the strip against the inner face of the insole lip, this rubbing action 70 being produced by longitudinal movement of the shaft 36 in response to a spring 78 the action of which is controlled by a cam, as disclosed in our prior patent.

A strip S of reinforcing material such as Gem 75

duck coated with pressure-responsive cement such as latex is led from a reel or supply of indefinite length over a pin 80 extending between ears 82 mounted on the upper arm 84 of a bell-crank lever pivoted at 86 and having an operating arm 88 through a hole in which a rod 90 passes. The rod 90 at its lower end is connected to an arm 92 fixed to the rockshaft 36. On the rod 90 above the operating arm 88 is a fixed collar 94 and below it is a sliding collar 96 between which and a fixed collar 98 is a spring 100. The purpose of the mechanism just described will be later explained. From the pin 80 the strip S is led through a slit near the end of a Z-shaped guide member 102 the lower end of which is secured at 104 to the arm 92 and hence to the rockshaft 36. Between its ends the member 102 carries ears 106 to which is pivoted a leaf spring 108. A screw 110 threaded through the member 102 bears against the spring and causes it to press upon the strip as it enters a lower strip guide member 112. This guide 112 (Fig. 5), as disclosed in our prior patent, is shaped to bend the rear marginal portion of the strip toward the right or toward the direction from which the insole is fed. The forwardly bent portion is then carried around an edge 113 formed on part of the guide 112 and brought into position parallel to the inner face of the rib against which it is pressed by the head 76. The remainder of the width of the strip engages the periphery of the head 76 and the peripheries of the three spurred disks 72, 73, 74 which constitute the applying roll and act to press the remainder of the strip against the body of the insole.

Each of the disks 72, 73, 74 is provided about its periphery with sharp spurs 114 which project beyond the disks an amount about equal to the thickness of the strip, the disks acting to control the application of the strip to the insole, as explained in our prior patent. In order to insure such control it is important that the strip be pressed throughout a substantial portion of its width against the spurs 114 after it comes in contact with the applying roll and before the applying roll presses the cemented face of the strip against a similarly cemented surface on the insole. For this purpose a finger 116 is formed at its lower end with a surface 117 corresponding in curvature to that of the disks 72, 73, 74 of the applying roll, which surface, as shown in Fig. 9, presses the strip against the applying roll except in the region of the points of the spurs 114, the pressing face 117 of the finger being provided with grooves 118 which prevent dulling of the points of the spurs 114 by contact with the pressing surface of the finger. The finger 116 is pivoted at 120 to a lug 122 secured to the arm 64 and has a portion 123 thereof extending above the pivot 120 and connected by a spring 124 to a pin 126 on the rockshaft 36. As heretofore, when the applying roll is moved out of its operative position, the finger 116 is automatically separated from the applying roll and when the applying roll is approaching its operative position the spring 124 becomes effective to press the finger 116 toward the applying roll to force the strip S upon the spurs 114.

In the illustrated machine a guide 128 (Fig. 8) to engage the inner face of the rib of an insole I is mounted on the finger 116 by screws 132 which pass through openings in the plate 130 larger than the screw and are threaded into the finger. The enlarged openings in the plate 130 enable the guide 128 to be adjusted both vertically with

respect to the bottom of the inside channel and laterally with respect to the inner face of the insole rib. The lower portion of the plate 130 is bent toward the applying roll (Fig. 7) and has a portion 134 which has been bent double to provide a rounded surface at 128 (Fig. 8) which bears against the inner face of an insole rib to form the guide as there shown. The plate 130 is extended rearwardly to provide a flange 136 (Fig. 8) which engages a stationary lug 138 secured to the upright 16 (Fig. 2). As the arm 64 is swung clockwise with the shaft 36 to carry the applying roll out of operative position, the flange 136 engages the lug 138 which prevents it from swinging with the arm 64 but permits it to move heightwise, the flange 136 merely sliding upwardly on the lug 138. When the applying roll is swung downwardly into operative position, a reverse movement takes place, the finger descending with the applying roll as they mutually approach each other and finally being moved by the applying roll away from the lug 138 against the pressure of the spring 124, the strip being thus firmly pressed against and impaled by the spurs 114 before the applying roll reaches the insole. Relative approaching movement of the roll and finger is limited by engagement of a surface 140 (Fig. 1) on a portion of the plate 130 secured to the finger 116 with a corresponding surface on the arm 64 which carries the applying roll.

As in the prior machine, an outside guide 142 (Fig. 8) is provided to engage the outer face of the rib and the feather of the insole, this guide being moved downwardly into operative position in conjunction with the movement of the upper feed roll 42 toward the insole. In the illustrated machine the guide 142, as shown in Fig. 2, is formed on the front end of a bar 144 the rear end of which is pivoted at 146 to the upright 14 and an intermediate portion pivoted by a screw 148 to the block 34 so that as the block 34 is raised and lowered to move the feed roll toward and from the insole the guide 142 receives similar movements, its movement away from the insole being limited by a stop 149 on the upright 16.

As in the machine of our prior patent, shears are provided for cutting off the strip and, as illustrated herein, the blades of the shears are arranged at an angle to the strip so that they sever the strip obliquely, as illustrated in Fig. 5. The shearing mechanism comprises a slide 150 the front portion of which is bent upwardly at about 30° from the horizontal and forms a blade 152. The slide 150 is held by gibs 153 to a supporting plate 155 (Fig. 4) secured at each end to a strut 151. A cooperating shear blade 154 is pivoted to the blade 152 at 156 and has a portion 158 (Fig. 4) extending rearwardly of its pivot 156 and bent to a position parallel with the slide 150. On top of the slide 150 is a shear-operating slide 160 mounted for movement in the same direction as the slide 150 and held in position by screws 162 passing through slots 164 in the slide 160 and threaded into the slide 150. The portion 158 is beveled as at 159 to enable it to clear the slide 160 as it turns about the angular axis 156. The slide 160 has an inclined slot 166 which is engaged by a barrel-shaped roll 167 on a stud 168 secured to the rearward extension 158 of the shear blade 154 and extending above the slide 160. With this construction it will be seen that movement of the slide 160 to the right (Fig. 4) with respect to the slide 150 will cause actuation of the blade 154 to close the shears and sever the

strip. Such movement, however, is initially prevented by a flap 170 having a straight edge 171 extending in the direction of the slide 160 and engaged by the upwardly projecting stud 168. 5 Since the force applied to the slide 160, because of engagement of the stud 168 with the flap 170, cannot move the slide 160 relatively to the slide 150, both slides move together to translate the shears bodily to operative position. When that position is reached the slide 150 is arrested by engagement of a pin 172 projecting downwardly from the slide 150 with the front end of a slot 174 formed in the fixed supporting plate 155. When the pin 172 reaches the end of the slot 174, however, the stud 168 is beyond the front end of the flap 170. Accordingly, the slide 160 may move relatively to the slide 150 and cause movement of the shear blade 154 relatively to the blade 152. The flap 170 is pivoted to fixed ears 176 on an axis parallel to the direction of movement of the slide 160 and is yieldingly held in horizontal position by a leaf spring 178 bearing against a square edge of the flap adjacent to its pivot. When return movement of the slides 150, 160 occurs, the stud 168 moves under the front end of the flap 170 and then out from under it, whereupon the flap drops again into its initial position when the slides 150, 160 have assumed their initial positions with respect to each other. Fig. 6 shows the flap 170 in section and the stud 168 at the time when it is moving rearwardly beneath the flap. Later the slot 166 will move the stud 168 to the right, causing it to engage a beveled surface 173 on the under side of the flap and lift the flap which falls back into its initial position when the stud 168 passes beyond the edge 171.

To move the slides a rockshaft 182 (Fig. 2) has an upwardly extending arm 184 at the upper end of which is a slot 186 (Fig. 5) through which passes a screw 188 threaded into the slide 160. The arm 184 is moved in a direction to retract the slides by a tension spring 190 connected at one end to a screw 192 on the arm 184 and at the other end to the frame. The rockshaft 182 has an arm 194 (Fig. 1) connected to the armature 196 of a solenoid 198 so that when the solenoid is energized, for example, in the manner disclosed in our prior patent, the arm 184 will be moved to the right against the spring 190, thus actuating the slide 160 and causing operation of the shears in the manner already explained.

As shown in Figs. 1 and 5, an arm 199 is secured to one of the gibs 153 of the shear mechanism and extends in a direction substantially parallel with the shear blades, said arm carrying at its outer end a combined insole stop and strip-forming tool 201. The forming tool 201 (Fig. 1) projects toward the right from the arm 199 and has a flat lower face against which the bottom of the insole is brought when the strip is to be severed. The heightwise extent of the tool 201 corresponds to the heightwise extent of the insole rib and when the shears 152, 154 have been moved bodily into their operative position the lower shear blade 152 rests against the rear edge of the forming tool 201 or against a plate 203 which may be applied to the top of the tool. The right-hand edge of the plate 203 is preferably straight to hold the strip substantially flat and parallel to the cutting edge of the blade 152 at the point where it is being cut. The right-hand end of the tool 201 has a formation adapted to force the strip into the angle between the inner face of the rib and the body of the insole, 55 the end face of the tool being inclined to corre-

spond substantially to the inward inclination of the rib and curved in plan to correspond more or less closely to the curve of the rib of a pointed toe.

The illustrated machine may be employed to practice the method disclosed in Letters Patent of the United States No. 2,255,353, granted September 9, 1941, in the name of S. M. Griswold, in which the reinforcing strip is laid along one side of the insole from toe to heel and then along the other side from heel to toe. After reaching the toe on the second side the operator allows the applying tool to swing upwardly, thus releasing the insole which he presents against the lower face of the forming tool 201 which is then beneath the applying roll in its upwardly swung position. The strip is now in the path of the shears which are operated to sever the strip at an inclination. The inclined end of the strip on the insole is formed into the angle between the rib and the body of the insole by pressing it against the tool 201 and turning it in contact therewith. Since the strip at the beginning of the operation is cut at the same angle as the strip at the end of the operation, the inclined end of the second strip may be laid over upon the inclined end of the first strip and still have some portion of the cemented face adjacent to its end come in contact with the cement on the insole, the second end being thus secured over the first without the necessity of applying cement to the end of the strip first laid in order to hold the end of the second strip in place. Secured to the arm 199 and extending across the ends of the shear blades 152, 154 is a guard plate 205 to prevent the operator's hands from being placed accidentally in the path of the shears when they are operated. Since the shear blades are tilted upwardly, the forming tool 201 is located higher than in the machine of our prior patent, thus giving more space above the feed roll 20 and making it more convenient for the operator to present the insole against the forming tool 201.

Under some conditions a strip containing thermoplastic stiffening material is employed, in which case it is desired to heat the strip before its application to an insole. For this purpose a long electric heating element 200 is mounted on a member 202 pivoted at 204 to the back of a casing 206 and normally hangs in a vertical position against a stop 207, being biased in that position by a tension spring 208 connected at one end to the member 202 above its pivot 204 and at the other end to a part of the machine frame. Current is supplied from any suitable source through a flexible conductor 210. When the rockshaft 36 is turned counterclockwise to carry the applying roll into operative position, the arm 92 (Fig. 1) swings upwardly, causing the collar 96 to apply pressure through the spring 100 to the arm 88 which, turning about the pivot 86, swings the strip guide 20 toward the heating element until a pin 212 extending between the ears 82 engages the heating element 200 above its pivot 204, thus swinging it counterclockwise against the tension of the spring 208 until its lower portion engages the guide 102. This mutual approaching movement of the strip guide and the heating element locates a considerable length of the strip in a position parallel to the heating element and at a uniform short distance therefrom to cause the strip to be heated as it passes to the applying roll. The applying roll may also be kept in heated condition by an electric heating element 214 mounted on the arm 64 75

and supplied with current through conductors 215 enclosed in a flexible casing 216.

When the applying roll moves toward its inoperative position, the tension of the spring 100 is relieved and the spring 208 acts to swing the heating element 200 about the pivot 204 out of the way of the applying roll. If, however, the spring 208 should fail to act promptly, the mechanism carried by the arm 64 might engage the heating element 200 and cause damage thereto. Accordingly, means is provided for positively moving the heating element out of the way of said mechanism as the applying roll moves to inoperative position. For this purpose a curved arm 218 is secured at 220 to the member 202 and extends upwardly to present a surface 222 in position to engage an extension of the pin 80 when the parts are in operative position, as shown in Fig. 1. Hence the clockwise movement of the applying roll mechanism to inoperative position first relieves pressure on the spring 100 and then causes the fixed collar 94 to engage the arm 88, causing positive clockwise movement of the arm 84 whereupon the pin 80, acting on the arm 218, positively moves the heating element 200 about its pivot 204 toward its vertical position out of the way of the mechanism carried by the arm 64. When sufficient movement of the heating element 200 has occurred to insure that the applying mechanism will clear its lower end, the upper end of the arm 218 has descended sufficiently, due to movement about the center 204, to permit the pin 80 to swing across the upper end of the arm 218, thus permitting further movement of the arm 84 to carry the strip still farther away from the heating element, the heating element 200 and the strip S being thus separated sufficiently so that no substantial heating of the strip occurs when the parts are in inoperative position.

The operating rods 24, 44 (Fig. 3) are connected to a lever 224 fulcrumed at 226. If a treadle were connected directly to the front end of the lever 224, depression thereof to pull downwardly on the rods 24, 44 would, in bringing various operating instrumentalities of the machine into operative position, place under tension several springs against which the operator would have to exert considerable effort during continuous operation of the machine. To make it easier to operate the lever 224 and to hold it in depressed position, a toggle comprising links 227, 228 is pivoted at one end to a lug 239 on the column 10 and at the other end to the lever 224. The joint of the toggle is connected by a link 232 to an upright arm 234 of an angle lever pivoted at 236, the other arm 238 of the angle lever constituting a treadle. Depression of the treadle 238 causes the toggle to be moved from a bent position to a nearly straight position, thus causing depression of the front end of the lever 224 to bring the operating instrumentalities of the machine into operative position and to cause power operation thereof. Of course very little effort is required to maintain the toggle in an almost straight position during operation of the machine.

Having thus described our invention, what we claim as new and desire to secure by Letters Patent of the United States is:

1. In a machine for applying a reinforcing strip to a ribbed insole, means for advancing the insole past an operating point, a freely rotatable applying roll having spurs about its periphery, said applying roll being movable into and out of

operative position with respect to said operating point, means for presenting a strip to the applying roll, and a finger having an extended surface acting to press the strip against the spurs on the roll, said surface having a groove opposite to the spurs to prevent contact of the spurs with said surface as the strip is pressed against the roll.

2. In a machine for applying a reinforcing strip to a ribbed insole, means for advancing the insole past an operating point, a freely rotatable applying roll comprising a plurality of disks each having spurs about its periphery, said applying roll being movable into and out of operative position with respect to said operating point, and a finger having an extended surface acting to press the strip against the spurs on a plurality of said disks, said surface having grooves opposite to the spurs to prevent contact of the spurs with said surface as the strip is pressed against the roll.

3. In a machine for applying a reinforcing strip to an insole, means for advancing the insole past an operating point, an applying roll movable into and out of operative position with respect to said operating point, said roll comprising a plurality of freely rotatable disks, each disk having a series of spurs on its periphery, means for guiding the strip to the roll, and means operating as the roll approaches the operating point to press said strip against the spurs on the plurality of said disks, said means having a plurality of grooves in its pressing surface to prevent dulling of the spurs.

4. In a machine for applying a reinforcing strip to a ribbed insole, means for advancing the insole past an operating point, an applying roll movable into and out of operative position with respect to said operating point, a carrier for the applying roll, a strip guide on said carrier, a finger mounted on the carrier, means for urging the finger toward the applying roll, means arranged to permit the finger to engage the strip on the applying roll during the movement of the applying roll toward the operating point, and a guide carried by said finger arranged to engage the inner face of the insole rib to which the reinforcing strip is to be applied.

5. In a machine for applying a reinforcing strip to a ribbed insole, means for advancing the insole past an operating point, an applying roll movable into and out of operative position with respect to said operating point, said roll comprising a plurality of freely rotatable disks, each disk having a series of spurs on its periphery, means for guiding the strip to the roll, a finger operating as the roll approaches the operating point to press said strip against the spurs on a plurality of said disks, said finger having a plurality of grooves in its pressing surface to prevent dulling of the spurs, and a guide carried by said finger and engaging the inner face of the insole rib.

6. In a machine for applying a reinforcing strip to a ribbed insole, means for advancing the insole past an operating point, an applying roll movable into and out of operative position with respect to said operating point, a carrier for the applying roll, a strip guide on said carrier, a finger mounted on the carrier, means for urging the finger toward the applying roll, means arranged to permit the finger to engage the strip on the applying roll during the movement of the applying roll toward the operating point, and a guide carried by said finger arranged to engage the inner face of the insole rib to which

the reinforcing strip is to be applied, said guide being constructed and arranged for adjustment vertically and laterally with respect to said rib.

7. In a machine for reinforcing ribbed insoles, means for applying a strip of material to the body of the insole and to the inner face of the rib, means for feeding the insole toward the applying means, means for pressing the strip against the applying means, a guide carried by said pressing means adapted to engage the inner face of the rib, and a guide engaging the outer face of the rib, said guides acting to direct the insole to the applying and feeding means.

8. In a machine for applying a reinforcing strip to a ribbed insole, means for advancing the insole past an operating point, a freely rotatable applying roll, said applying roll being movable into and out of operative position with respect to said operating point, means for presenting a strip to the applying roll, a finger acting to press the strip against the roll, and a guide carried by said finger and adapted to engage a face of the insole rib.

9. In a machine for reinforcing ribbed insoles, means for applying a strip of material to the body of the insole and to the inner face of the rib, upper and lower feed rolls for feeding the insole toward the applying means, means for moving the upper feed roll toward and from the insole, a finger for pressing the strip against the applying means, a guide carried by said finger adapted to engage the inner face of the rib, and a guide engaging the outer face of the rib and connected to said upper feed roll for movement therewith toward and from the insole.

10. In a machine for reinforcing ribbed insoles, means for applying a strip of material to the body of the insole and to the inner face of the rib, means comprising upper and lower feed rolls for feeding the insole toward the applying means, said upper feed roll being movable toward and from the feather portion of the insole, means for pressing the strip against the insole, and a guide engaging the feather of the insole and connected to the upper feed roll for movement therewith, said guide acting to direct the insole to the applying and feeding means.

11. In a strip-laying machine, means for feeding the work, means for applying a strip of reinforcing material to the work, a pair of shears comprising blades pivoted to each other, said blades being arranged at an oblique angle to the lengthwise dimension of the strip, a horizontal slide carrying both shear blades, and means for operating the shears to sever the strip from edge to edge at an oblique angle to form strip ends having one angle acute and the other obtuse.

12. In a strip-laying machine, means for applying a strip to the work, a first horizontal slide having its end portion tilted upwardly at a substantial angle to the slide and formed as a shear blade, a lever pivoted to the up-tilted portion of the first slide having one end formed as a shear blade co-operating with the first-mentioned shear blade and its other end lying parallel with said slide and carrying a stud, a second slide movable in the same direction as the first slide and having an inclined slot engaging said stud, and means for operating said second slide to move the shear blades into operative relation to the strip and then to operate the pivoted shear blade to sever the strip.

13. In a strip-laying machine, means for ap-

plying a strip to the work, a stop against which the work may be raised at the conclusion of an applying operation, a first horizontal slide arranged to move toward the stop and having its end portion tilted upwardly at a substantial angle to the slide and formed as a shear blade, a lever pivoted to the up-tilted portion of the first slide and having one end formed as a shear blade co-operating with the first-mentioned shear blade and its other end lying parallel to said slide and carrying a stud, a second slide movable in the same direction as the first slide and having an inclined slot engaging said stud, and means for operating said second slide to move the shear blade into operative relation to the strip and then to operate the pivoted shear blade to sever the strip.

14. In a machine for applying strip material to shoe parts, the combination of strip-supplying means, a strip-applying roll movable toward and from its operating point, a strip guide remote from the applying roll, an angle lever having a fixed pivot on one arm of which the remote guide is carried, a strip guide adjacent to the applying roll, manually operated means for moving the applying roll toward the operating point, a heating device pivoted to hang in a vertical position, and means acting as the applying roll approaches the operating point yieldingly to actuate the other arm of the angle lever to move the remote guide to engage the heating device above its pivot and swing it against the adjacent guide, thus disposing a length of the strip between the guides in parallel relation to the heating device.

15. In a machine for applying strip material to shoe parts, the combination of strip-supplying means, a strip-applying roll movable toward and from its operating point, means for holding a portion of the strip in extended condition be-

tween the supplying means and the applying roll, manually operated means for moving the applying roll toward the operating point, a heating device, means acting as the applying roll approaches the operating point to move the heating device toward the extended portion of the strip, and means acting positively as the applying roll moves away from the operating point to restore the heating device to its initial position.

16. In a machine for applying a strip of material stiffened with thermoplastic material to the body of the insole to reinforce it, the combination of strip-laying means movable toward and from the insole, means for guiding the strip to the laying means, means for feeding the insole, strip-heating means pivoted to hang by gravity in a vertical plane, means for moving the strip-laying means toward the insole and simultaneously effecting mutual movement between the heating means and the strip-guiding means to bring the strip and the heating means into proximity, and means acting positively to move the heating means toward its normal position during the early part of the movement of the applying means away from the insole.

17. In a machine for applying a reinforcing strip to a ribbed insole, means for advancing the insole past an operating point, a freely rotatable applying roll movable into and out of operative position with respect to said operating point, an operating lever depressible to move the roll toward its operating point, a toggle connected between a fixed support and the lever, and a treadle lever connected to the joint of the toggle so that operation of the treadle lever straightens the toggle and depresses the operating lever.
